(57) **CLAIM**

The ornamental design for a heating module for a contact lens warming apparatus, as shown and described.

DESCRIPTION

FIG. 1 is a top plan view of a heating module for a contact lens warming apparatus showing our new design;

FIG. 2 is a rear elevational view thereof;

FIG. 3 is a right-side elevational view thereof;

FIG. 4 is a front elevational view thereof;

FIG. 5 is a left-side elevational view thereof;

FIG. 6 is a bottom plan view thereof;

FIG. 7 is a front perspective view thereof; and,

FIG. 8 is a rear perspective view thereof.

The broken lines in the drawing views are included for the purposes of illustrating portions of the heating module for a contact lens warming apparatus that form no part of the claimed design.
